Attorney

UNITED STATES PATENT OFFICE.

ROBERT R. FREUND, OF EVANSVILLE, INDIANA.

BACK SUPPORT.

Application filed January 10, 1928. Serial No. 245,732.

This invention relates to body supporting apparatus, and has for one of its objects to provide a novel, simple and highly efficient apparatus of this character which shall be 5 adapted to support the back in a manner to prevent strain on the muscles thereof, which will not retard the movements of the body while at work, and which cannot become displaced by the movements of the body while 10 standing or sitting or while assuming a standing or a sitting posture.

A further object of the invention is to provide a body supporting apparatus of the character stated which shall be adapted to support 15 the abdomen and utilize the movements of the body to effect the massaging of the abdomen, and which shall be adapted to be readily adjusted for application to persons of different sizes.

20 With the foregoing and other objects in view, the nature of which will appear as the description proceeds, the invention consists in the construction, combination and arrangement of parts hereinafter fully described and claimed, and illustrated in the 25 accompanying drawing, wherein:

Figure 1 is a view in front elevation of the body supporting apparatus in applied position,

30 Figure 2 is a view in front elevation of the body supporting apparatus arranged for application, and

35 Figure 3 is a sectional view taken on the vertical plane indicated by the line 3—3 of Figure 1.

The body supporting apparatus comprises a strap 1 which is of sectional formation and provided with elastic inserts 2. The front ends of the sections of the strap 1 are connected by buckles 3 and tabs 4, and the rear ends of the sections are connected by a buckle 3a. The strap 1 extends about the abdomen, and rests upon the hips, and its elastic inserts 2 contact with the abdomen. Arms 5 which 40 are arranged at the sides of the body directly above the hips, are secured at their lower ends to the strap 1 by brackets 6. The arms 5 comprise lower members 7 which are screw threaded and connected directly to the brackets 6, and upper members 8 which are tubular and internally screw threaded and adjustably engaged with the lower members so as to permit the length or height of the arms to be varied. Arcuate rests or crutch members 9,

which are equipped with pads 10 and engage under the arms, are provided with downwardly extending screw threaded stems 11 which are slidably arranged in the upper ends of the tubular members 8. Flanged nuts 12 and 13 are adjustably mounted on the arm member 7 and the stem 11, respectively, and springs 14 are arranged on the arms 5 between the nuts and yieldingly support the arm rests 9. The springs 14 extend above the arms 5, and the tension thereof may be varied by 60 adjusting the nuts 12 on the arm members 7. The nuts 13 and the upper ends of the arms 5 limit the downward movement of the rests 9, and the movement of the rests in this direction may be varied by adjusting these nuts 70 on the stems 11. A sectional strap 15 which extends about the chest, is connected to the stems 11. The front ends of the sections of this strap are connected by a buckle 16, and the rear ends of these strap sections are connected by a buckle 17.

From the foregoing description, taken in connection with the accompanying drawing, it will be understood that the apparatus functions to yieldingly support the shoulders, and 80 that due thereto the muscles of the back are relieved from strain. As the strap 1 extends about the abdomen and is provided with elastic inserts 2 which are tensioned during the application of the strap, the abdomen is supported and subjected to a massaging action 85 during the movements of the body. As the rests 9 are yieldingly supported, the apparatus will not retard the movements of the body and will not make the wearer uncomfortable. 90 As the springs 14 may be placed under various tensions, the apparatus may be adjusted to suit requirements of different persons, and this, together with the adjustability of the straps 1 and 15, permit the device to be adapted 95 for use by persons of different sizes.

It should be understood that the drawing is merely illustrative and does not pretend to give exact proportions. Furthermore, the said drawing is illustrative of a preferred construction, it being my expectation that various changes and modifications may be made without departing from the spirit and scope 100 of my invention.

What is claimed is:—

1. A supporting apparatus of the character set forth, comprising an abdominal strap, arms adjustable as to length and secured to the 105

strap, shoulder rests slidably associated with the arms, and springs carried by the arms and yieldingly supporting the rests.

2. An apparatus of the character set forth, comprising an abdominal strap, arms adjustable as to length and secured to the strap, shoulder rests slidably associated with the

arms, straps adjustably associated with the rests for contact with the arms, members adjustably associated with the arms, and springs positioned between the straps and members. 10

In testimony whereof I affix my signature.

ROBERT R. FREUND.
